DEVICE FOR BENDING SHEET METAL INTO CYLINDRICAL SHAPES

William H. Mann and Elmer V. Schmidt, Winona, Minn., assignors to Hossfeld Manufacturing Company, Winona, Minn., a corporation of Minnesota

Application October 7, 1948, Serial No. 53,302

4 Claims. (Cl. 153—39)

1

Our invention relates to improvements in metal bending devices and, more particularly, for bending sheet metal into cylindrical shapes.

An object of this invention is to provide a simple and highly efficient device for bending sheet metal into cylindrical shapes, such as bushings of a size smaller than can be bent on conventional bending rolls.

Another object of this invention is to provide a device that will bend stock right up to the end, which permits the bending of a piece of sheet metal of a given length into a cylinder of a pre-determined diameter without waste or cutting after the bend is completed.

A further object of this invention is to provide a device, by the use of which, cylinders of various different diameters can be bent simply by the use of interchangeable mandrels of different diameter.

These and other objects of the invention will be apparent from the following detail description and the accompanying drawings.

To the above end, generally stated, the invention consists of the novel devices and combination of devices hereinafter described and defined in the claims.

In the accompanying drawings, which illustrate the invention, like characters indicate like parts throughout the several views.

Referring to the drawings:

Fig. 1 is a plan view of the bending device;

Fig. 2 is a side elevational view of the same, some parts sectioned on the line 2—2 of Fig. 1;

Fig. 3 is a fragmentary detail view partly in plan and partly in section taken on the line 3—3 of Fig. 2, on an enlarged scale;

Fig. 4 is a view partly in side elevation and partly in section taken on the line 4—4 of Fig. 3;

Fig. 5 is a plan view of the die removed from the stationary and bending frames, the mandrel being removed from the center pin which is shown by means of broken lines; and

Fig. 6 is a perspective view of a cylinder formed on the mandrel.

The numeral 1 indicates a stationary frame comprising upper and lower duplicate flat bars 8 and 9, respectively. These bars 8 and 9 are intermediately connected by a spacing member 10 and a nut-equipped bolt 11. Rearwardly of the spacing member 10, the bars 8 and 9 are inwardly offset to reduce the distance therebetween and are connected by front and rear spacing sleeves 12 and nut-equipped bolts 13. The frame 1 is supported on a pair of leg brackets 14 bolted at 15 to a bench or other support, indicated by a single

line 16. Formed in the bars 8 and 9, forwardly of the spacing members 10, is a plurality of longitudinally spaced holes 17.

A swinging lever-acting frame 18 extends between the frame bars 8 and 9, at the front end portions thereof. This swinging frame 18 comprises upper and lower duplicate bars 19 and 20 that are identical with the bars 8 and 9. A short handle 21 extends between the contracted end portions of the bars 19 and 20 and is rigidly secured thereto by nut-equipped bolts 22. This handle 21 takes the place of the spacing sleeves 12 for the frame 1. The bolt 23 corresponds to the bolt 11 and the co-operating spacing member is not shown. Formed in the bars 19 and 20 is a plurality of longitudinally spaced holes 24 that correspond to the holes 17. In the free end portions of the bars 8 and 9 is a pair of aligned large holes 25 and a corresponding pair of large holes 26 are formed in the bars 19 and 20.

The swinging frame 18 is connected to the stationary frame 1 by a pin 27 that extends through a pair of the aligned holes 17 and the pair of the aligned holes 24. This pin 27 has a head 28 that rests on the upper bar 8 and holds said pin suspended therefrom.

The stationary frame 1 and the swinging frame 18 are not new but afford a highly efficient device for the embodiment of our invention.

Referring now in detail to our invention, to wit: a die for forming cylindrical shapes from sheet metal which includes a vertically disposed bending block 29. This bending block 29 is rigidly secured to an upright sleeve 30 by a pair of diverging plates 31 secured to the outer vertical portions of said bending block. The sleeve 30 is pivotally secured to the swinging frame 18 by a wrist pin 32 which extends therethrough. The end portions of the wrist pin 32 are held in the first pair of aligned holes 24 offset from the pivot pin 27 toward the handle 21. The sleeve 30 rests on the lower frame bar 20 and the wrist pin 32 extends between the bars 8 and 9 and is held thereby against endwise movement.

The bending block 29 rests on and is rigidly secured to a U-shaped spacing and guide member 33 which slidably rests on the lower frame bar 9. This member 33 is of the same thickness as the lower frame bar 20 on which the sleeve 30 and side plates 31 rest. A center pin 34 extends through the large holes 25 in the frame bars 8 and 9 and is supported at its lower end on a member 35 secured to the lower frame bar 9. This center pin 34 extends between the prongs of the spacing and guide member 33 and holds said member for

straight line sliding movement on the lower frame bar 9.

A cylindrical mandrel 36 is removably mounted on the center pin 34. A sheet of metal x , partly bent to cylindrical form, is held pressed against the mandrel 36 by the two side members of the bending block 29 at their outer vertical end portions, which afford contact points 37. The metal sheet x is shaped about the mandrel while held pressed thereagainst, by a multiplicity of short bends. The bends are made by pulling the lever-acting swinging frame 18 toward the center pin. The first operation in bending the sheet x around the mandrel 36 will bring the two contact points 37 of the bending block 29 into contact with said sheet and bend the same between the two contact points 37 around the mandrel 36. Succeeding operations of the lever-acting frame 18 will first move the bending block 29 away from the mandrel 36 to permit said sheet to be fed by hand between the contact points 37 and then move the bending block 29 toward the mandrel 36 and, at which time, one of the bending block contact points 37 engages the curved portion of the sheet x and holds the same pressed against the mandrel 36 and the other contact point 37 engages an unbent portion of the sheet x and bends the same around the mandrel 36. These operations are repeated until the sheet x is bent into cylindrical form y and removed from the mandrel 36, see Fig. 6. During the operation of the bending block 29, the U-shaped member 33 is guided by the center pin 34 for straight-line movement and holds the bending block 29 for action on the sheet x being bent. By the short bends imparted to the sheet x , it is possible to bend the same up to its outer end so that the sheet x forms a complete cylindrical shape with its ends in abutting engagement without waste and the necessity of cutting. In actual use of the die, mandrels of different external diameter will be provided for specific jobs.

To remove a mandrel, it is only necessary to lift the center pin 34 to withdraw the same from the mandrel, substitute another mandrel of a different external diameter therefor, place the same on the guiding and spacing member 33 in alignment with the center pin 34 and drop said pin through the replaced mandrel, between the prongs of the member 33, through the hole 26 in the lower frame bar 9 and onto the stop member 35.

The drawings illustrate a commercial form of the invention, but it will be understood that the same is capable of certain modifications as to details of construction, arrangement and combination of parts within the scope of the invention herein disclosed.

What we claim is:

1. In a die of the class described, a stationary frame, a lever-acting member pivoted to the frame, a center pin on the frame, a removable cylindrical mandrel on the center pin, a V-shaped bending block having side members arranged to press a sheet of metal onto the mandrel at circumferentially spaced points, a wrist pin on the lever-acting member, a sleeve on the wrist pin, and a pair of side plates rigidly secured to the sleeve, said side plates being in diverging relation from the sleeve to receive the bending block therebetween, said side plates being rigidly secured to the side members of said bending block.

2. The combination with a stationary frame having upper and lower bars, a swinging frame having upper and lower bars extending transversely between the first noted bars and pivoted thereto, of a die including a center pin mounted in aligned holes in the bars of the stationary frame, a cylindrical mandrel on the center pin, a V-shaped bending block having side members arranged to press a sheet of metal onto the mandrel at circumferentially spaced points, a wrist pin mounted in aligned holes in the bars of the swinging frame, a sleeve on the wrist pin, and a pair of side plates rigidly secured to the sleeve, said side plates being in diverging relation from the sleeve to receive the bending block therebetween, said side plates being rigidly secured to the side members of the bending block.

3. The structure defined in claim 2, further including a spacing and guide member on the lower end of the spacing block and loosely resting on the lower bar of the stationary frame and having a slot through which the center pin extends.

4. The structure defined in claim 2, further including a U-shaped spacing and guide member on the lower end of the bending block, the transverse portion of said member extending transversely under the side plates and straddling the center pin.

WM. H. MANN.
ELMER V. SCHMIDT.
